(57) **CLAIM**

The ornamental design for a shroud for a blending container, as shown and described.

DESCRIPTIONFIG. 1 is a perspective view of a shroud for a blending container showing our new design;
FIG. 2 is a front view thereof;
FIG. 3 is a rear view thereof;
FIG. 4 is a top view thereof;
FIG. 5 is a bottom view thereof; and,
FIG. 6 is a bottom perspective view thereof.

(Continued)

The broken lines in the figures are included for the purpose of illustrating portions of a shroud for a blending container or its environment and form no part of the claimed design.

1 Claim, 4 Drawing Sheets
